UNITED STATES PATENT OFFICE.

EMIL STERN AND WLADISLAW PACIORKIEWICZ, OF CHARLOTTENBURG, GERMANY.

SELECTIVE MECHANISM FOR VENDING APPARATUS.

1,009,265.

Specification of Letters Patent. Patented Nov. 21, 1911.

Application filed November 29, 1910. Serial No. 594,636.

To all whom it may concern:

Be it known that we, EMIL STERN and WLADISLAW PACIORKIEWICZ, subjects of the German Emperor, residing at 10 Tauentzienstrasse, Charlottenburg, Germany, have invented certain new and useful Improvements in Selective Mechanism for Vending Apparatus, of which the following is a specification.

10 This invention relates to vending apparatus provided with a selective mechanism, which has for its object to select from a number of piles of articles, that are arranged in horizontal and vertical rows in a show case, 15 one single pile, so as to permit the delivery of the desired article without interfering with the others. The piles of articles may comprise piled up plate-shaped, tablet-shaped or packet-shaped single pieces such 20 as boxes and the like, whereupon by suitable holding devices and releasing means, the removal or release of the lowermost or foremost single packet is effected each time.

The construction of the invention is explained according to the following specification by way of example in connection with an automatic vending machine, from which packets of tablet-shaped articles are delivered selectively after the insertion of a coin 30 and by the operation of a handle.

Referring to the accompanying drawings, Figure 1 is a front elevation of the vending apparatus, part of the show plate being omitted so as to show the arrangement of the selective mechanism; Fig. 2 is a detail side elevation of the coin passage and the coin-free operable sliding handle; Fig. 3 is a partial side elevation showing the arrangement of the selector-fingers with respect to the rocking yokes for the piles; Fig. 4 is a plan of one of the pile holders and yokes on an enlarged scale; Fig. 5 is a detail plan in horizontal section on the line A—B of Fig. 1, whereby the operation of the rocking rod with its eccentric-shaped cam is shown in engagement against a tilting frame; Figs. 6 and 7 are views on an enlarged scale (front elevation and plan) which show the index adjusting device for the selective mechanism; Figs. 8 and 9 are views which show the coin slide handle in two positions as supplementary to Fig. 2.

The apparatus box *a* is covered at the front by a front-plate *b* which is provided with 55 glass-covered peep-holes or is completely

transparent, such plate being shown only fragmentarily in Fig. 1. The peep-holes indicate at 1, 2, 3, 4, 5, 6, 7, 8, 9, the places where the magazines *m*¹, *m*² . . . *m*⁹ are arranged within the apparatus-box; they are so arranged in horizontal and transverse rows that the selection of one magazine-pile results at that place where one of the horizontal rows is crossed by a vertical row. In the example shown, only nine spaces for piles are assumed, which are arranged in three horizontal and three vertical rows; it is obvious that a larger or smaller number of the magazines can be employed in rows.

The holding bars adapted for the magazines and extending through the apparatus-box transversely, are designated *c* in Fig. 3; they are omitted in the remaining figures for the sake of clearness. The magazines are detachably hooked on to the bars *c*. 75 Each of the magazines *m*¹ *m*² . . . *m*⁹ is adapted to have its contents ejected by suitable mechanism actuated by a selector-finger *f*¹ *f*² . . . *f*⁹. They are suspended from sliding rods *v*¹, *v*², *v*³ in articular connection 80 and, so far as they are swung forward in their engaging position, they control the operating members, by means of which the lowermost packet is ejected from the piles. According to the constructional form of the 85 magazine-pile as shown, the operating member employed is in the form of a rocking yoke *j* (Figs. 3 and 4), whose side-pieces *j*¹ and *j*² are in the form of bell-crank levers and carry on their lower ends spring members *i* with tappets or pins *i*¹. It is obvious from Fig. 3 that when causing a rocking movement of the yoke *j* with spring members *i* in consequence of the engagement of the tappets or pins *i*, the lowermost packet 90 of the pile is advanced in a lateral guide until it arrives at the front to be freely dropped as indicated by dotted lines in Fig. 3. The packet then drops into a collecting trough *d*, which is provided on the lower 95 part of the apparatus-box and is accessible from without through a delivery slot *e* (Fig. 3) so that the packet can be taken out.

The rocking backward of the yoke *j* takes place automatically under spring action; 105 there are provided at the sides of the pile-holder, switch-like guides *w*, along which the rearward sliding pins *i*¹ are led in order to return to the initial position of engagement only when the yoke has completed its 110

return rocking stroke. During the effective forward movement, the pins v slide over the guides w . Thus this arrangement permits that during each rocking movement of the yoke, a single packet is released from the piles and conveyed to the delivery orifice.

Each of the yokes j is provided with an engaging pin or 'detent' z (Figs. 3 and 4). This pin is located within or near to the path of the selector-finger $f^1, f^2 \dots f^9$ belonging to the respective pile. The said selector-fingers are controlled in their rocking position by a rocking frame or yoke with a horizontal lifting rod h^1, h^2, h^3 . The 10 guide links $k^1 k^1, k^2 k^2$ and $k^3 k^3$ form the suspending members for the said lifting rods which, as shown in Fig. 3, extend behind the selector-fingers of each horizontal row and with which tilting frames or 15 brackets are formed. The tilting or lifting movement of the lifting rods takes place from the side and through the medium of a vertical sliding rod u which is also rotatable and has three eccentric-cams u^1, u^2, u^3 belonging to the three horizontal rows. 20 The said eccentric-cams are mounted on the sliding rod u and at such variable distance from each other that either only the uppermost cam the middle cam or the bottom cam 25 engages during a certain lifting position with the lifting rod h^1, h^2 or h^3 . It is assumed in the drawing (Figs. 1 and 3) that the uppermost lifting rod h^1 is under the action of the eccentric-cam when the 30 sliding rod rotates on the axis, as shown in Fig. 5. It will be hereinafter described how the rotating or rocking motion is derived 35 from the coin-free mechanism.

Owing to the described movement of the 40 tilting bracket or the rocking movement of the lifting rod (h^1) caused by eccentric-cams, all of the selector-fingers of one horizontal row are shifted into such a position that their lower ends are ready for engagement 45 over the pin z of the rocking frame or yoke j . The further swinging or rotation of the selector-fingers on the rod $v^1 v^2 v^3$ is limited by an abutment. If the sliding rod $v^1 v^2$ or v^3 is moved downward—for which purpose 50 selective mechanism hereinafter described is adapted—as soon as the above described engagement of one of the selector-fingers has taken place, the said selector-finger moves onto the pin z of the rocking yoke j , causing 55 the same to rock and a packet to be ejected in the previously described manner. It is obvious that this action of delivery of the packet only takes place in connection with that magazine-pile, which belongs to 60 the horizontal row of the rocking yokes moved by means of tilting frames or brackets.

While the operation in the respective horizontal row, where the selected magazine m^2 is located, is derived in the described

manner—in consequence of the rocking motion of the vertical sliding rod u with cams u^1, u^2, u^3 —a similar selective moving mechanism is adapted to selectively move downward one of the sliding rods $v^1 v^2$ or v^3 so that the effective operation is imparted to the place where such vertical row and the respective horizontal row cross each other.

An axially slidable sleeve r is mounted on 75 a rocking transverse rod s (Figs. 1, 3 and 6) and has three detents or tappets r^1, r^2, r^3 which are at such a variable distance from each other with respect to the position of the three rods v^1, v^2, v^3 that always only one 80 of them is in a position of coincidence and ready for operation so as to enter into engagement with the hook-shaped lower end thereof. It is assumed in Figs. 1 and 6 that the middle pawl or detent r^2 is in a position 85 ready for engagement on the rod v^2 .

The rocking rod s is adapted to make a rocking motion in the same manner and approximately at the same time as the sliding rod u with eccentric-cams u^1, u^2, u^3 . The 90 sliding sleeve r takes part in this rotation and the pawl r^2 of the same therefore comes against the hooked shoulder of the rod v^2 in the position indicated—which is positively moved downward. The three selector-fingers f^1, f^2, f^3 belonging to the rod v^2 95 move downward in consequence of the motion of the rod and as only the uppermost finger f^2 is moved into the engaging position according to the preceding rocking 100 motion of the lifting rod h^1 , this finger f^2 alone performs the operation on the rocking frame j belonging to the magazine m^2 and provided with pin or detent z , whereas the 105 remaining selector-fingers are idle.

It is obvious from Figs. 1 and 6 that if the sliding sleeve r were shifted to the right or to the left, the pawl r^3 or r^1 would be operated instead of the pawl r^2 and the rod v^3 or v^1 rendered operative accordingly. 110 Thus the selection of any vertical row with respect to any horizontal row of the magazines is possible and dependent on the adjustment of the sliding sleeve r and the vertical sliding rod u respectively. The differential adjustment of the said parts r and u is effected by the following described construction, which, however, only serves as a suitable means, because other means may also be employed for the selective adjustment of these parts. It is obvious that the selective determination of the adjusting position for the rod u as well as for the sliding sleeve r may be derived separately and automatically from certain handle slides 115 combined with indexes. In the combined-construction as shown in Figs. 1 and 6, the adjusting movement is derived in one common function.

According to Figs. 1 and 6 the rocking 120

shaft s bears a bevel wheel s^1 engaging with another bevel wheel s^2 , which is a part of a sleeve or hollow shaft u^* , which can rotate in a suitable bearing a^1 without however being capable of a longitudinal displacement. The vertical sliding rod u extends downwardly through the said sleeve u^* and is taken along during the rotation of the same in consequence of groove and feather engagement. It is obvious that owing to the engagement of the bevel wheels s^1 s^2 a coupling for simultaneous rocking motion is insured between s and u^* , whereupon the longitudinal adjustment of the 15 sliding rod u and that of the tubular slide r can take place independently of such common rotary motion. The shaft s is provided at its end with a sector-shaped wing y , which is the operated member in the mechanism of 20 the coin slide (Figs. 8 and 9).

The adjusting means (Figs. 6 and 7) consist essentially of a lever or articulated member p with slide q and connecting rod q^1 . The latter is linked to the tubular slide r . 25 The lever p is double-armed and adapted to rotate at a^2 ; its one arm forms a support for the shifting rod p^1 which can be slid parallel to the rod u and is provided above with a fork p^2 , whereby it is adapted, when engaging under a collar of the rod u , to raise or lower the latter according to the angular 30 adjustment of the lever p . The slide q forms with its tracer and knob q^* the member to be operated by hand; the notches 1, 2, 3 ... 9 35 serve as indices, which are provided in a slotted guide or index plate n (Figs. 6 and 7) with slots in the same order as the magazines m^1 m^2 ... m^9 which are arranged in horizontal and vertical rows.

40 The adjustment of the tracer either on the top, middle or lower lever thus determines a corresponding angular position of the lever p and a corresponding elevation of the shifting rod p and the vertical sliding rod 45 u ; thus, in the position as indicated in Fig. 1, the adjustment takes place with respect to the top horizontal row where the top cam u^1 of the eccentric cams of the rod u exerts its action when the latter is rocked. The 50 lateral or horizontal adjustment of the tracer on one of the index-notches 1, 2 ... 9 effects by means of the connecting rod q^1 a corresponding adjustment of the tubular slide r on the rocking shaft s , whereby according to the adjustment, the extension r^1 55 r^2 or r^3 is moved into the proper position in order to be adapted during the rocking motion of the shaft s or tubular slide r to meet the coincident hooked-shaped part of the rod v^1 or v^2 or v^3 . According to the 60 position as indicated in Figs. 1 and 6, the adjustment is such that the rod v^2 is operated and consequently the selector-finger f^2 is also operated.

65 The coin-slide mechanism is shown not

only in Figs. 1 and 2 but also in Figs. 8 and 9. g is the coin-slide adapted to be drawn out at the front by means of a knob; a spring g^* tends to draw it into the normal position (Fig. 8). The bifurcated inner end of the 70 coin-slide forms the receiver for the coin x , which drops out of the coin passage l (from the coin slot l^*). The sides of the receiver are connected to a ledge g^1 and a cam-slot g^2 is provided on the side of the receiver 75 so as to serve as a guide for a pin or peg y^2 , protruding laterally from the wing y , which also extends into the bifurcated receiver. Normally, when no coin is in the receiver, the coin-slide can be reciprocated 80 idly owing to the straight length of the cam-slot g^2 , wherein the pin y^2 slides idly to and fro. The wing y possesses besides the pin y^2 a slot y^1 , into which the ledge g^1 may slide ineffectively during the idle movement 85 of the coin slide.

If a coin x is received by the coin slide g before its outward movement, the coin rests between the ledge g^1 and the wing y , as shown in Fig. 8. During the outward movement, the coin therefore takes the wing with it and imparts a rocking motion thereto, because the pin y^2 slides in the upwardly bent end of the cam slot. Owing to the upward swinging movement of the wing y , 95 the coin finally loses its support and drops through an opening of the receiver into the collecting chamber. The rocking movement imparted to the wing y is transmitted to the previously described rocking members 100 u and r and results in the operation of the properly positioned selector-finger or releaser in connection with one of the magazines.

The ledge g^1 serves for holding back subsequently following coins x , which may have 105 been previously inserted in the coin channel. The herein described operation may be repeated according to the number of inserted coins. The described releasing mechanism (selector-fingers, tilting brackets, etc.) 110 may also be so modified that the articles can be released at the front from magazines having vertically instead of horizontally piled packets.

What we claim and desire to secure by 115 Letters Patent is:—

1. In vending apparatus, the combination of a plurality of superposed rows of article magazines, ejecting mechanism appurtenant to each magazine, operating members for 120 said ejecting mechanism arranged in series in correspondence with the ejecting mechanism, a rod supporting each series of operating members and holding the latter normally away from the ejecting mechanism, cams on said rod, means whereby said rod may be moved to bring one of the 125 cams into engagement with one of the series of operating members, means for depressing one of said operating members into engage- 130

ment with one of the ejecting mechanisms, and means adapted to simultaneously revolve said rod and act on the said depressing means whereby an article may be ejected 5 from a predetermined magazine.

2. Vending apparatus with selective mechanism comprising a set of magazines arranged in several horizontal and several vertical rows, a number of tilting members each 10 belonging to one horizontal row, a number of vertical sliding rods, each belonging to one vertical row and having selector-fingers which are adapted to coöperate with the releasing devices of the said magazines and adjusting means consisting of a longitudinally 15 adjustable vertical rocking shaft, which is provided with cams in a differential arrangement and is adapted to operate the tilting members, also a horizontally adjustable and 20 likewise rocking shaft with differentially arranged tappets, which are adapted to operate one of the vertical sliding rods, and means for imparting the rocking motion to

the two rocking members, substantially as described.

3. In a selective vending apparatus of the kind specified, a selective mechanism comprising a pair of lengthwise shiftable rocking members provided with differentially shaped cams, a lever controlling with its 30 one end the stroke of the one vertical member and provided on the other end with a tracer-slide, the tracer playing in a slotted index plate arranged according to the order of the horizontally and vertically disposed 35 magazines, whereupon the differential movement of the tracer-slide is imparted to the other horizontally sliding member, substantially as described.

In testimony whereof we affix our signatures in presence of two witnesses.
